UNITED STATES PATENT OFFICE.

HERBERT THEODORE BALLARD, OF NORRISTOWN, PENNSYLVANIA.

LET-OFF MECHANISM FOR KNITTING MACHINES.

Original application filed March 26, 1921, Serial No. 455,924. Divided and this application filed March 1, 1922. Serial No. 540,224.

To all whom it may concern:

Be it known that I, HERBERT T. BALLARD, a subject of the King of Great Britain, and resident of Norristown, county of Montgomery, and State of Pennsylvania, have invented certain new and useful Improvements in Let-Off Mechanism for Knitting Machines, of which the following is a specification, division of application Serial Number 10 455,924.

The invention concerns means for stopping the machine when a bunch of fibre or other obstruction occurs at the needles or when a broken needle occurs.

15 In the accompanying drawings—

Figure 1 is a view of so much of a knitting machine embodying my invention.

Fig. 1^a is a view of the catch holding the let-off rod.

20 Fig. 2 is a sectional view of the knitting head.

Fig. 3 is a plan view, with the bobbin stand supporting posts in section.

25 In the drawings 1 indicates the needle cylinder which is clamped to the fixed frame 4' by a nut 5. A plate 14 rotates on the frame and carries a flange 16 to which the lower needle cam section 11 is attached by screws. The upper cam section 10 is carried by a ring 12 which is supported by 30 posts 13 from the plate 14.

The yarn guides, two in number are shown at *a*, *b*, and they are supported on the ring 12 to rotate therewith.

35 I have provided means whereby the machine will be stopped when a bunch or a damaged needle occurs, said means including a detector finger 28 pivotally mounted at 29 upon the ring 12 and having its inner 40 end lying close to the needle to be affected by an irregularity in the knitting, and when this occurs, the detector finger will be swung aside withdrawing its outer end from under a collar 30 slidably mounted upon one of the 45 posts 22 and pressed normally downward by a spring 31 so that when the detector finger operates, the collar 30 will be forcibly thrown down into line with a latch 32 and as the collar travels with the rotary part of 50 the head it will come against the latch 32 and withdraw it against the tension of its spring 33 from engagement with the vertical plunger 34 which will then be forced downwardly by its spring 35 to operate the resetting lever 36. This lever is pivotally mount-

ed at 37 and is provided with a handle 38. The depression of this lever removes its catch 39 from the let-off rod 40 so that this may be operated by any suitable spring to shift the belt and thus stop the machine. 60 The plunger 34 bears normally upon the resetting lever 36 so that when the operator resets the lever 36 in position to hold the let-off for the operation of the machine the plunger 34 will be lifted so that the catch 32 65 will engage its upper portion and retain it until the next automatic stopping action occurs. This arrangement will prevent the operator from starting the machine without restoring the plunger 34 to its normal position for operation. 70

The yarn is fed to one of the guides from an overhead bobbin 20 which is supported upon the cross-piece 21 mounted on the posts 22 extending up from the revolving head of 75 the machine. The yarn from this bobbin passes up through a guide eye 23 and thence laterally and downward through the hollow post or rod 24 from whence it passes to one of the yarn guides. 80

The other yarn is drawn from a bobbin 25 supported in fixed relation to the machine upon a standard 26 and this yarn is delivered through guides 27 to the other one of the hollow rods 24 from the lower end of which 85 the yarn runs directly to the other yarn guide.

Certain features of structure disclosed herein and not claimed form the subject matter of another application filed by me 90 February 11th, 1922, Serial No. 535,912.

I claim:

1. In combination in a circular knitting machine, a fixed cylinder, a revolving member carrying needle cams, a post extending up from the revolving member, a member encircling and slidable on said posts, a spring for pressing said member downwardly, a detector finger for holding said member normally up, a latch supported on the 100 fixed frame and adapted to be struck by the said slidable member when in its lowermost position, and as the latter travels with the rotary member, and stop motion connections controlled by the latch, substantially as described. 105

2. In combination in a circular knitting machine, a fixed cylinder, a revolving member carrying needle cams, a post extending up from the revolving member, a member 110

- slidable on said post, a spring for pressing said member downwardly, a detector finger for holding said member normally up, a latch supported on the fixed frame and 5 adapted to be struck by the said slidable member when in its lowest position and as the latter travels with the rotary member, and stop motion connections controlled by the latch, sub- 30
- 10 including a vertically movable plunger, a spring for pressing said plunger downwardly, a resetting lever upon which said plunger normally rests and which is restored to its set position to be engaged by 15 the latch when the resetting lever is restored to normal position, substantially as described.
- 11 3. In combination in a knitting machine, a knitting head having a needle cylinder and 20 rotary needle cams, a bobbin stand rotating with the needle cams, a post for supporting the bobbin stand above the knitting head, a member encircling and slidable upon the said post, a detector finger for holding said 25 encircling member normally up, a latch supported on the fixed frame and adapted to be
- struck by the said slidable member when in its lowest position and as the latter travels with the rotary member, and stop motion connections controlled by the latch, sub- 30
- 35
4. In combination in a knitting machine, a knitting head, having a needle cylinder and rotary needle cams, a bobbin stand rotating with the needle cams, a post for supporting the bobbin stand above the knitting head, a member encircling and slidable upon the said post, a detector finger for holding said encircling member normally up, a latch supported on the fixed frame and adapted 40
- 45 to be struck by the said slidable member when in its lowest position and as the latter travels with the rotary member, and stop motion connections controlled by the latch, said knitting head including a ring 12 for supporting the upper section of the cam ring and said detector finger being mounted on the said ring, substantially as described.

In testimony whereof, I affix my signature.

HERBERT THEODORE BALLARD.
